UNITED STATES PATENT OFFICE.

SANDY H. LOVE, OF COLT, ARKANSAS, ASSIGNOR OF ONE-FOURTH TO ARCHIE L. NUNN
AND ONE-FOURTH TO ARMSTU P. HAMPTON, BOTH OF COLT, ARKANSAS.

GUN.

1,301,143.

Specification of Letters Patent.

Patented Apr. 22, 1919.

Application filed March 6, 1918. Serial No. 220,765.

To all whom it may concern:

Be it known that I, SANDY H. LOVE, a citizen of the United States, residing at Colt, in the county of St. Francis and State of Arkansas, have invented certain new and useful Improvements in Guns; and I do hereby declare the following to be a full, clear, and exact description of the invention, such as will enable others skilled in the art to which it appertains to make and use the same.

This invention relates to guns, and more particularly to a revolver structure which is positioned underground and is operated by the depression of a tread structure to automatically discharge the gun or revolver for killing the person who treads upon the tread or bridge structure.

The invention is particularly designed for use in guarding camps, warehouses, supply stations, or other similar places or buildings, so as to eliminate the necessity of the employment of night watchmen to protect the building, and it comprises, generally, a pair of gun structures including barrels which have revolving magazines or cylinders associated therewith together with means for automatically revolving the magazines or cylinders in the gun to position the cartridges in alignment with the bore of the barrels, and also means for automatically operating the hammer structure to discharge cartridges when a person stands upon the tread member which is positioned at a distance from the gun structure, and in front of the barrels of the gun, so that the projectile discharged from the gun will strike the person standing upon the tread member.

With the foregoing and other objects in view this invention consists in such novel features of construction, combination and arrangement of parts as will be hereinafter more fully described, illustrated in the accompanying drawings, and claimed.

In describing the invention in detail, reference will be had to the accompanying drawings wherein like characters designate like and corresponding parts throughout the several views and in which:

Figure 1 is a side view of the gun showing it in position.

Fig. 2 is a top plan view.

Fig. 3 is a vertical longitudinal section through one of the gun structures.

Fig. 4 is a horizontal section through a part of the gun structure.

Fig. 5 is a section through the tread structure.

Fig. 6 is a detail cross section through the bridge end of one of the gun structures.

Fig. 7 is a detail perspective view of the housing for inclosing the gun, and

Fig. 8 is a side elevation of a modified form of the gun structure.

Referring more particularly to the drawings, 1 designates a housing or casing for the gun structure, which is constructed of any suitable material and has doors 2 formed in the sides of the same to permit access to the interior of the casing for inspection and reloading of the gun structures.

The gun structure proper includes a base 3 which has bars 4 extending longitudinally along the edges of the same, and a rearwardly extending inclined bar 5, which is braced by a suitable angularly disposed bracing bar 6. Suitable braces 7 and 8 are attached to the brace bars 5 and 6 and extend upwardly therefrom, as clearly shown in Fig. 1 of the drawing. The brace bar 7 is attached to a member 9 formed on the under surface of the gun barrels 10 while the brace bar 8 extends upwardly behind the rear ends of the revolving magazines 11 of the gun structure. The brace 7 is braced by a suitable brace 12 which is attached to the plate bar 4. The magazine 11 is rotatably supported, upon trunnions 14, as is ordinary in revolvers or side arms including a revoluble magazine and it is provided with a plurality of chambers 15, preferably ten or more in number, which receive the cartridges, the projectiles of which are forced outwardly through the bore 16 of the barrel 10, by the explosion of the cartridge.

The outer surface of the chambers or magazines 11 are provided with a plurality of notches extending circumferentially about the magazines which notches provide shoulders 17 that are engaged by the upper end of a pawl 18. The pawl 18 is slidably supported by suitable guides 19, and it has a flat spring 20 positioned within the guides which holds the upper end of the pawl in engagement with one of the shoulders 17 of the cylinder. The lower end of the pawl 18 is connected to a rod 21, which rod is

rockably supported by suitable supporting arms 22. The rod 21 extends through one end of a bar 23 which is pivotally supported by suitable standards 24, intermediate of its 5 ends, so that upon the rocking of the lever 23, the rod 21 will be rocked for moving the pawl or trigger 18 vertically, to rotate the magazine 11 one step, to move one of the chambers thereof into alignment with the 10 bore 16 of the gun barrel 10. A suitable resilient catch structure 25 is provided for preventing reverse rotation of the cylinder or magazine 11.

The upper end of the brace or support 8 15 is provided with an opening 26, in which is mounted the firing pin 27. This firing pin, may be of the ordinary construction used in exploding the cartridges used in guns of this nature and it is operated by 20 the operation of a hammer 28. The hammer 28 is pivotally supported as shown at 29, and the head 30 thereof is positioned for striking the firing pin 27 when the hammer is operated, through the rocking of the trigger lever 23. The hammer 29 is forced into 25 a firing position by a flat spring 31, which is attached to the support 8 and has its upper end seated in a recess 32 formed in the hammer 30.

30 The hammer structure 28 is cocked by the rocking of the rod 33, which rod is bent intermediate its end to form a substantially U-shaped portion 34, the bight portion of which is connected to the trigger lever 23.

35 The ends of the rod 33 are bent at right angles to the main portion of the rod as shown at 35, and since there are two guns employed in the construction of the improved gun structure, both ends of the rod 40 33 are bent to form hammer operating members 35 as clearly shown in Figs. 3 and 4 of the drawings.

The angled end 35 of the rod 33 engages 45 a pivoted wear member 36 which is pivotally connected to the hammer structure 28 and is held in its normal position by a flat spring 37. The pivoted wear member 36 is provided and held in an outward extended position by the spring 37 so as to permit 50 of pivotal movement of this wear member under the rocking movement of the end 35 of the rod 33, so as to allow a yieldable connection between the end 35 and the hammer 28 to permit the hammer to be forced 55 into a firing position by the action of the spring 31 without being impeded in its movements by the angled end 35 of the rod 33. Coil springs 38 are connected to the bight portion of the U-shaped portion 34 60 of the rod 33 and to the bar 6, for returning the rod 35 and the trigger lever 23 to their normal positions after they have been operated by the rocking of the operating lever 40. The operating lever 40 is pivotally supported by a suitable supporting structure 65

41, carried by the supporting structure of the gun, and the rear end of the operating lever 40 is connected to the trigger lever 23, by bars 42, rearwardly of the pivot of the operating lever 40. The operating lever 40 70 extends forwardly from the muzzles of the guns, beneath the ground, as clearly shown in Fig. 1 of the drawings, and it has its forward end connected to the forked ends 43 of a vertically movable rod 44. The rod 44 75 has its upper end attached to the under surface of a tread or bridge 45 which is positioned at any desired distance from the gun structure and projects only a very short distance above the surface of the ground, 80 as clearly shown in Fig. 1 of the drawings. The bridge or tread 45 has a pair of guide bars 46 connected to the ends of the same, and the lower ends of these guide bars extend through suitable openings 47 formed 85 in the top of a casing 48 for the tripping mechanism of the guns. The rod 44 has a head 49 formed upon the lower end of the same, which is slidable in a vertical cylinder 50 positioned within the casing 48. A helical spring 51 is mounted in the cylinder 50 and engages the head 49, for holding the tread 45 in its upward position, until the tread is depressed by the weight of a person walking or stepping upon the same. 95

In the operation of the improved structure, the gun mechanism or structure is placed in a suitable pit as clearly shown in Fig. 1 of the drawings, and it is inclosed by the casing 1 so as to prevent dirt or other 100 foreign matter from interfering with the operativeness of the gun structure and the chambers of the magazine or cylinder 11 are filled with cartridges. The gun is then ready for operation. It will be noticed in the 105 drawings that a pair of the gun structures are employed, and they are connected to operate simultaneously. The two gun structures are identical, and in the foregoing description, only one of them has been described but it is to be understood that the other gun structure is identical in construction with the one described with the exception of the fact that the barrel 10 thereof is elevated more than the barrel 10 of the first 110 described gun, so that it will shoot higher than the first gun will shoot, as clearly shown in Fig. 1 of the drawings.

After the gun has been properly set, any person treading upon the tread or bridge 120 45 will move this member downwardly and consequently move the rods 44 downwardly which will rock the operating lever 40 upon its pivot. The rocking of the lever 40 upon its pivot, will in turn rock the trigger lever 125 23, and rock the rod 33, to move the ends 35 of this rod into engagement with members 36 and force the hammers 28 rearwardly against the tension of the springs 31. When the ends 35 of the rod 33 reach the 130

limit of their upward movement, they will pass off of the lower ends of members 36, allowing the hammers to be forced forwardly into its normal position by the action of the springs 31 which will cause the hammers to strike the firing pin 27, and fire the cartridges with which the firing pins aline. During the operation of the rod 33 to fire the cartridge, the rod 21 will be rocked to move the pawl 18 downwardly so that it will engage in one of the ratchets 17 of the cylinder below the one in which it was previously engaged. Then when the springs 38 return the rod 33 and the trigger lever 23 to their normal position, the magazines or cylinders of the gun structures will be rotated one step, moving the cartridge next to the one which was just fired into alinement with the pin, and resetting the gun for operation upon the depression of the tread 45. The barrels 10 of the guns are arranged so that the bullets projecting from the muzzles thereof will strike the person who depresses the tread 45 and kill him.

In Fig. 8 of the drawings, a modified form of the invention is shown, which modified form is identical in construction with the preferred form heretofore described, in all respects with the exception of the fact that the gun structure is mounted upon a portable cart as indicated at 70, which cart is supported by suitable supporting wheels 71 so that it may be easily transported from one place to another. The operating lever 30 of the modified form of the gun instead of extending forwardly between the barrels of the guns extends rearwardly thereof and is pivotally supported by a suitable standard 72, carried by the truck structure. In 40 the modified form, the gun structure is adapted to be moved or pushed in front of the operator, and he can by downward pressure upon the outer end 73 of the operating lever 48 operate the gun structure in the same manner in which the preferred form 45 is operated, so as to discharge the cartridges.

A suitable rod 100 is provided for forcing the empty shells out of the magazine. This rod is preferably carried by a part of the gun structure, when not in use, as indicated in Fig. 1 of the drawings.

From the foregoing description taken in connection with the accompanying drawings the advantages of construction and the method of operation of the improved gun will be readily apparent to those skilled in the art to which this invention appertains and, while in the foregoing description, the principle of the operation of this invention 55 has been described together with various features of construction, it is to be understood that certain minor features of construction, combination and arrangement of parts may be altered to suit practical 60 conditions provided such alterations are

comprehended within the scope of what is claimed.

What is claimed is:

1. In a device as set forth, the combination, of a gun structure, a tread structure, 70 means operable by the depression of said tread to discharge said gun structure, and means operable by the depression of said tread to recharge said gun structure.

2. In a device as set forth, a pair of guns, 75 a tread, means operable upon the depression of said tread for simultaneously firing said guns.

3. In a device as set forth, a gun structure including a rotatable magazine, firing 80 means, means for rotating said magazine so as to bring cartridges carried thereby into alinement with the gun barrel and the firing means, a tread member, and means operable by said tread member for operating said 85 firing means and said magazine rotating means.

4. In a device as set forth, a gun structure, including a barrel, a rotatable magazine, 90 a hammer, a pivotally mounted trigger lever, means for operating said trigger lever to operate said hammer and means operated by said trigger lever to rotate said magazine.

5. In a device as set forth, a gun structure, including a rotatable magazine, a hammer, 95 a pivotally mounted trigger lever, means operated by the operation of said trigger lever to operate said hammer, a tread, and means connecting said trigger lever and said tread to operate the trigger lever upon depression 100 of the tread, and means operable by depression of the tread for causing intermittent rotation of said magazine so as to cause cartridges carried thereby to be brought into alinement successively with the barrel of the 105 gun and with said hammer.

6. In a device as set forth, a gun structure, including a rotatable magazine, a hammer, a pivotally mounted trigger lever, means operated by the operation of said trigger lever 110 to operate said hammer, a tread, and means connecting said trigger lever and said tread to operate the trigger lever upon depression of the tread, and means operable by the return movement of said trigger lever to its 115 normal position for rotating said magazine.

7. In a device as set forth, the combination, of a pair of gun structures each including a barrel, rotatable magazines, hammer structures for firing cartridges carried 120 by said magazine, means for rotating said magazines for feeding cartridges in alinement with the barrels of the guns, a trigger lever, means operable by said trigger lever for operating said hammer, and means operable by the return movement of said trigger lever to its normal position to rotate said 125 magazines.

8. In a device as set forth, the combination, of a pair of gun structures each in- 130

cluding a barrel, rotatable magazines, hammer structures for discharging cartridges carried by said magazines, means for rotating said magazines for feeding cartridges in alinement with the barrels of the guns, trigger levers, means operable by said trigger lever for operating said hammers, means operable by the return movement of said trigger lever to normal position to rotate 10 said magazines, a movable tread member,

and means connecting said tread member and said trigger levers for operating the trigger levers upon depression of the tread member.

In testimony whereof I affix my signature 15
in presence of two witnesses.

SANDY H. LOVE.
